UNITED STATES PATENT OFFICE.

CHARLES HOUBEL, OF TOLEDO, OHIO.

DESIGN FOR BIRD-CAGE BRACKETS.

Specification forming part of Design No. 7,754, dated September 8, 1874; application filed July 23, 1874.
[Term of Patent 14 years.]

To all whom it may concern:

Be it known that I, CHARLES HOUBEL, of the city of Toledo and county of Lucas, in the State of Ohio, have invented or produced a new and original Design for a Bird-Cage Bracket, of which the following is a specification:

This design relates to an adjustable bracket for attachment to a vertical wall or other surface for the purpose of suspending bird-cages in different positions.

The design consists in the peculiar ornamental shape or conformation for the swinging hook-arm or crane, and end-caps or bearing-knobs for attaching and supporting the same, hereinafter set forth, the prominent ornaments being figures of acorns.

The figure of the accompanying drawing is a face view of an adjustable bird-cage bracket illustrating this design.

The drawing represents an adjustable bird-cage bracket, consisting of three parts, namely, a horizontally-swinging hook-arm or crane, A, carrying at its extremity a depending hook, h, and end-caps or bearing-knobs B C, by which the former is attached to a wall or other surface.

The ornamental shape or conformation applied to these parts is as follows: The crane A is made in the form of the letter F, with its main vertical member a, horizontal members b c, and a supplemental vertical member, d,

uniting the latter, ornamented by circumferential rings of diversified shapes, as represented. A spherical ball, e, is arranged at the intersections of the members c d, and vertical acorns f f², which constitute the prominent ornaments, are arranged at the extremity of the horizontal arm b and at the bottom of the ball e. The upper end-cap or bearing-knob B is chiefly spherical or spheroidal, terminating at bottom in a flaring neck with horizontal rings. The lower end-cap C is chiefly in the form of a large acorn, terminating at top in a corrugated neck. Spherical knobs g g² g³ g⁴, are applied at the different extremities of the bracket other than that at which the hook h is located, as represented. The parts are all circular, or nearly circular, in cross-section.

The F shape of the swinging arm, and the other features of ornamentation herein described, are not claimed as new except as applied or associated in manner substantially as herein set forth.

The following is claimed as new, namely:

The ornamental design for an adjustable bird-cage bracket, comprising the figures of acorns f f² and spherical knobs g g² g³ g⁴, at extremities of the bracket, substantially as herein shown and described.

CHARLES HOUBEL.
